John R. Wood Inventor
By his Attorney Parker W. Page.

UNITED STATES PATENT OFFICE.

JOHN R. WOOD, OF NEWARK, NEW JERSEY, ASSIGNOR TO NEW PROCESS MULTI-CASTINGS COMPANY, OF NEWARK, NEW JERSEY, A CORPORATION OF NEW JERSEY.

MOLDING.

Application filed May 24, 1922. Serial No. 563,273.

To all whom it may concern:

Be it known that I, JOHN R. WOOD, a citizen of the United States of America, residing at Newark, in the county of Essex and State 5 of New Jersey, have invented certain new and useful improvements in Molding, of which the following is a full, clear, and exact description.

This invention is an improvement in the 10 art of molding or casting objects of metal in sand or other molds. It consists in a novel process or method of producing what are known as metal matched pattern plates by means of which the cope and the drag sec- 15 tions or members of an ordinary mold may be made. The process of molding metal parts may be most expeditiously and eco- nomically carried out by the use of such matched plates instead of by means of the 20 ordinary patterns which have to be drawn from each mold, but the obstacles to their use are numerous, particularly the difficulty of making them, which, up to the present time, is a practically unsolved problem from 25 a commercial standpoint. The present invention, however, affords a quick and easy means of making such plates in a perfectly satisfactory condition.

The method of producing these matched 30 plates hereinafter described is novel so far as its general character is concerned, and the specific details involved are not of the es- sence of the invention, as these may be great- 35 ly modified, as will be understood by those skilled in the art. In general terms, the new process is as stated below.

I first form two follow boards, a drag and a cope follow board, and upon the former is laid a pattern of the object to be cast or 40 molded. If any special follow boarding be required to back out the pattern, or in other words, to fill out the hollows or concavities on the under side of the pattern, this is done in the usual way by attaching to the drag 45 follow board a suitably shaped block of wood, although it is sometimes desirable and convenient to form this backing by running into the pattern a composition composed of finely divided carbon, plaster of Paris and 50 sawdust made sufficiently fluid for the pur- pose and permitted to set, or this composition made as a plastic may be molded into the back of the pattern and allowed to harden and then withdrawn.

55 The cope follow board may also be formed

in the usual way by hollowing out a block of wood attached to the cope follow board, or it may be formed by placing on the drag follow board with its pattern side bars or boards to form an enclosing frame, and fill- 60 ing in this frame with the same plastic com- position which when set is lifted out and attached to the cope follow board.

Having now my two follow boards, I pro- 65 ceed as follows: The drag follow board with the pattern laid thereon is made the bottom of a mold which is packed in the usual man- nuer with sand. The follow board is then re- 70 moved and the perfect sand mold containing the pattern is then inverted and made the lower section of a two-part flask with closed 75 bottom but open top. The empty upper sec- tion is then packed with sand in the usual man- nuer, a board secured over the open top, the two sections of the flask drawn apart, 80 and the pattern removed from the drag sec- tion.

I then place this drag section with the 85 impression of the pattern thereon over the drag follow board with its wood or plastic back- 90 ing, but separate the two by strips of a fusible metal laid along their sides and se- cured to the drag follow board. This forms a mold which is turned upon its side or end and poured with Babbitt or white metal. By 95 this means the space within the mold is com- pletely filled with metal which fuses the edges of the metal strip so that these are united to and become an integral part of the 100 pattern plate formed by this operation.

I then do the same thing with the cope 105 mold and cope follow board; that is to say, the two are brought together and properly secured with fusible metal strips of the same thickness laid along their sides and secured to the cope follow board. This mold is then turned on end and poured in the same way, and the cope board then removed.

There are thus produced a drag follow 110 board and a cope follow board. Each with a perfectly matched pattern plate secured thereto which may be used in the usual and ordinary way in making molds. That they are perfectly matched follows from the fact that they are made from the same pattern in a single mold, and the process of producing them precludes any such unevenness, irregu- 115 larities and differences as are inevitably found to exist between matched plates made in any other known way.

With the above description the drawings hereto annexed require but little description.

Referring to the same:

5 Fig. 1 is a sectional view of the drag follow board with a backed pattern thereon.

Fig. 2 is a sectional view of the associated 10 cope and drag follow board, showing the pattern in place and the filling of plastic material on its opposite sides.

Fig. 3 is a sectional view of the cope follow board with its plastic filling and separated from the drag.

Fig. 4 is a sectional view of a sand flask 15 member or section associated with the drag follow board and pattern, rammed and closed.

Fig. 5 is a sectional view of the upper 20 part or flask member of Fig. 4 with the pattern in the sand, associated with another flask member which is rammed and closed.

Fig. 6 is a sectional view of the upper 25 part or flask member of Fig. 5 associated with the cope follow board of Fig. 3 showing the fusible strips interposed between the two and secured to the cope follow board.

Fig. 7 is a similar view of the underpart 30 of Fig. 5 with the pattern removed associated in the same way with the drag follow board with its plastic backing.

Fig. 8 is a sectional view of the finished 35 or complete cope follow board with its attached matched plate; and

Fig. 9 a similar view of the drag follow 40 board and its attached matched plate.

The numeral 1 designates the pattern, 2 the drag follow board, and 3 the plastic backing for the pattern. In Fig. 2, 4 is the cope follow board, 5 the sides or frame, and 45 6 the plastic filling. In Figs. 4 and 7, 7 represents the sides, 8 the cover and 9 the sand filling of the flask section. In Figs. 5 and 6, 10 represents the sides, 11 the cover, 12 the sand, 13 the usual retaining pins or 50 posts of the flask sections, and 14 the usual devices for joining the two flask sections together. In Fig. 8, 15 is the completed metal matched pattern plate attached to the cope follow board, and in Fig. 9, 16 is the complete metal matched pattern plate attached to the drag follow board. In Figs. 6 and 7, 17 are the fusible metal strips.

As indicated above the process has been described in its preferred form. In carrying it out other materials than those named, and other known ways of obtaining impressions and castings may be employed, but as a whole the process is broadly new for the purpose set forth.

60 What I claim is:

1. The method of making metal matched pattern plates herein described, which consists in forming cope and drag follow boards

with impressions of the opposite sides of the same pattern in a hard material, making sand molds with impressions of the opposite sides of the same pattern, and by means of the same associated with but spaced from the corresponding follow boards to form molds and by means of the same, molding the matched pattern plates of relatively fusible metal.

2. The method of making metal matched pattern plates herein described, which consists in forming a drag follow board with a pattern thereon backed by a hard material, forming a cope follow board with the impression of the upper side of the pattern in hard material, forming a sand mold member of the said drag follow board with the pattern thereon, separating the same with the pattern in it from the drag follow board, forming a second mold member from the first with the attached pattern, and by means of said two sand mold members associated with but spaced from the corresponding follow boards to form molds, molding the matched pattern plates of relatively fusible metal.

3. The method of molding matched pattern plates herein described, which consists in forming the mold therefor with sides of a metal which is fused by that poured into the mold so as to become the edges and an integral part of the plate molded.

4. The method of making matched pattern plates herein described, which consists in associating the two members of a flask to form a mold therefor and separating the said two members by strips of fusible metal which form the sides of the mold space to be filled, and which become united to and integral with the plate when molded.

5. The method of making metal matched pattern plates comprising the following steps, forming a drag follow board with a pattern thereon with a follow boarding or backing of a hard material, forming from this device a cope follow board with the impressions therein, forming from the same device with the pattern thereon an impression in rammed sand, forming from this impression with the pattern in it a rammed sand impression, and forming with these impressions and the aforesaid follow boards molds for the pattern plates.

6. The method set forth in claim 5 with the additional steps of separating the two members used to form the molds by fusible metal strips, and securing said strips to the follow boards, whereby they will become fused by and integral with the metal poured to form the plates.

In testimony whereof I hereto affix my signature.

JOHN R. WOOD.
